(57) **CLAIM**

The ornamental design for a garment with a stand-up collar, as shown and described.

DESCRIPTION

FIG. 1 is a front view of a garment with a stand up collar showing my design according to a first embodiment;

FIG. 2 is a right-side view thereof;

FIG. 3 is a left-side view thereof;

FIG. 4 is a front view with the garment with a stand up collar partially opened;

FIG. 5 is a back view of the garment with a stand up collar shown in FIG. 1;

FIG. 6 is a left perspective view thereof;

FIG. 7 is a right perspective view thereof;

FIG. 8 is a cross-sectional side view of the garment with a stand up collar of FIG. 1;

FIG. 9 is an exploded two-dimensional pattern view of the garment with a stand up collar of FIG. 1;

FIG. 10 is an exploded two-dimensional pattern view of a garment with a stand up collar showing my design according to a second embodiment;

FIG. 11 is a front view of a garment with a stand up collar showing my design according to a third embodiment;

FIG. 12 is a front view with the garment with a stand up collar partially opened;

FIG. 13 is a left perspective view of the garment with a stand up collar of FIG. 11; and,

FIG. 14 is an exploded two-dimensional pattern view of the garment with a stand up collar of FIG. 11.

The dashed broken lines in the drawings illustrate portions of the garment that form no part of the claimed design. The short dash broken lines in FIGS. 25 to 27 represent stitching that forms part of the claim.

1 Claim, 13 Drawing Sheets
